T. A. CONLON

TRAIL CONNECTION

Filed Dec. 22, 1925

UNITED STATES PATENT OFFICE.

THOMAS A. CONLON, OF SILVER SPRING, MARYLAND.

TRAIL CONNECTION.

Application filed December 22, 1925. Serial No. 77,078.

(GRANTED UNDER THE ACT OF MARCH 3, 1883; 22 STAT. L. 625.)

The invention described herein may be used by the Government, or any of its officers or employees in prosecution of work for the Government, or by any other person in the 5 United States, without payment to me of any royalty thereon, in accordance with the act of March 3, 1883.

This invention relates to trail connections and has particular reference to connections 10 between the trail of a gun and its spade and limber.

When a gun mounted on a wheeled carriage is prepared for action the trail is connected to a spade or spades embedded in the 15 ground and in the traveling position it is connected to the carriage limber.

The principal object of the present invention is to provide a trail connection whose elements are alternately employed in preparing the carriage for action or travel and which fulfills all of the requirements demanded for each application of their use.

To these and other ends, my invention consists in the construction, arrangement, and 25 combination of elements, described herein-after and pointed out in the claims forming a part of this specification.

A practical embodiment of the invention is illustrated in the accompanying drawing, 30 wherein:

Fig. 1 is a longitudinal sectional view through a limber showing the connection of a trail member thereto;

Fig. 2 is a plan view thereof;

Fig. 3 is an enlarged detail view in plan of one of the clamping units;

Fig. 4 is a view in elevation showing the connection of the trail member to a spade;

Fig. 5 is an elevation of the rotatable 40 clamping member.

Referring to the drawing by numerals of reference:

In carrying out the invention the trail member or members 5 of a gun carriage are 45 each formed with an aperture 6 adjacent its rear extremity for the purpose of receiving a stud 7 on an anchoring or connecting member, such as a spade 8 or a limber 9. In the case of the limber, the stud or studs are 50 preferably located immediately forward of the axle.

The trail is further provided on its upper side with a transversely disposed cleat 10 having forked arms 11 adapted to receive swing bolts 12. Suitably shaped collars 13 55 on the bolts are held against arms 11 by means of the usual nuts 14.

The swing bolts 12 on the limber 9 are preferably universally mounted for convenience in hanging them when not in use. When 60 employing a split trail, I prefer in the traveling position to engage only the outer arms of the cleats 10 as the proximate disposition of the trail members permits the use of a single swing bolt 15 having a freely rotatable 65 clamping member 16 of sufficient length to span the trail members. A nut 17 for securing the clamping member in place is provided with peripheral recesses 18 for receiving a latch pin 19. This swing bolt may be 70 very favorably positioned in rear of the limber axle where it more effectually serves to hold the trail in place when the carriage is to be moved backward.

It will be seen that by the present arrangement a very simple and effective connection is established between the trail and either the spade or the limber, and the trail is not encumbered with any elements which are not used in both applications. 75

While in the foregoing there has been illustrated and described such combination and arrangement of elements as constitute the preferred embodiment of my invention, it is nevertheless desired to emphasize the 85 fact that interpretation of the invention should only be conclusive when made in the light of the subjoined claims.

I claim:

1. A gun carriage embodying a trail member provided with an aperture, a cleat having forked arms secured transversely on the trail, a limber to which the trail is adapted to be connected for traveling, a spade to which the trail is adapted to be connected for firing, and similar means on the limber and spade for engaging the aperture and forked arms of the trail. 90

2. In combination, a gun trail provided with an aperture and a transverse cleat having forked arms and a member to which the trail may be connected, said member pro- 100

vided with a stud receivable in the aperture of the trail and with bolts for engaging the forked arms of the cleat.

3. A gun carriage embodying a split trail, each trail member provided with an aperture and a cleat, a limber, a pair of studs on the limber insertable in the apertures of the trail members, swing bolts on the limber for

engaging the cleats, a single swing bolt mounted on the limber in rear of the axle 19 and between the trail members, a freely rotatable clamping member on said bolt adapted to span the trail members, and means for securing said clamping member.

THOS. A. CONLON.
